UNITED STATES PATENT OFFICE.

HENRY I. WRIGLEY, OF CHICAGO, ILLINOIS, ASSIGNOR TO UNIVERSAL DRAFT GEAR ATTACHMENT CO., A CORPORATION OF ILLINOIS.

DRAFT GEAR FOR RAILWAY CARS.

Application filed June 3, 1919. Serial No. 301,467.

To all whom it may concern:

Be it known that I, HENRY I. WRIGLEY, a citizen of the United States, and resident of Chicago, county of Cook, and State of Illinois, have invented certain new and useful Improvements in Draft Gears for Railway Cars, of which the following is a specification, and which are illustrated in the accompanying drawings, forming a part thereof.

The invention appertains to the tandem type of draft gear in which two sets of cushioning elements are employed, being arranged in alignment.

The objects of the invention are to generally improve upon and simplify this type of draft gear.

The invention consists in a structure such as hereinafter described and as illustrated in the accompanying drawings, in which—

Fig. 1 is a side elevation of the draft gear, the drawbar and its extension or yoke being shown in detail;

Fig. 2 is a plan section on the line 2—2 of Fig. 1;

Fig. 3 is a transverse section on the line 3—3 of Fig. 2;

Fig. 4 is a side elevation corresponding to Fig. 1, showing a modification;

Fig. 5 is a section on the line 5—5 of Fig. 4; and

Fig. 6 is a transverse section on the line 6—6 of Fig. 5, Figs. 4, 5 and 6 being drawn to a slightly smaller scale than Figs. 1, 2 and 3.

A pair of center sills for a car are shown at 10, 11, and to each sill is secured a draft lug 12, 12, and a buffing lug 13, 13. The butt of the draw-bar is represented at 14, and the yoke which constitutes an extension of the draw-bar and is suitably attached thereto and incloses the gear proper is shown at 15.

The improved draft gear comprises a pair of followers 16, 17, the one cooperating with the draft shoulders 12, 12, and the other with the buffing shoulders 13, 13. From each of these followers there projects inwardly, that is to say, toward the other follower, a pair of side plates, those associated with the follower 16 being shown at 18, 19, and those associated with the follower 17 being shown at 20, 21.

Arms 22, 23, project inwardly from the

median portion of each of the side plates 18, 19, and at their extreme ends are united by a cross plate 24. Arms 25, 26, extend from the top and bottom portions, respectively, of the side plate 21, and like arms extend from the top and bottom portions of the plate 20, the lower arms only, 27, associated with the plate 20 appearing in solid lines in the drawings; the upper arm, 28, associated with the plate 20 being shown in dotted lines in Fig. 3. Cross plates 29, 30, unite, respectively, the ends of the upper arms 25, 28, and the lower arms 26, 27. The arms associated with the plates 20, 21, are spaced apart to freely receive therebetween the arms 22, 23, associated with the plates 18, 19. These arms must bear the full load of the car and resist the shocks incident to the starting, stopping and travel of the same, at all times, and since the force exerted tends to compress the arms instead of to extend the same, it is necessary that these arms be made sufficiently strong to resist distortion. In order not to unnecessarily increase the amount of material which would add to the cost of manufacture and weight of these articles, the plates are made comparatively light and are reinforced with laterally extending flanges which extend along the plates and the arms attached thereto. The flanges on the arms 25, 26, 27 and 28 are arranged on the adjacent edges thereof, whereby the flanges not only reinforce these arms but also form a broad bearing surface for the cross plate 24.

The cushioning elements are interposed between the followers, and the cross plates are interposed each between one of the followers and the cross plate or plates associated with the other follower. In the exemplification of the device shown in the drawings, these cushioning elements take the form of springs, as 31, 32, the former being interposed between the follower 16 and the cross plates 29, 30, and the latter being interposed between the follower 17 and the cross plate 24. When the gear is at rest the two followers are in engagement with the draft and buffing lugs, and the cushioning elements are fully expanded.

In draft the follower is drawn forwardly by the yoke 15, compressing the spring 32 against the plate 24, and the plates 29, 30, compressing the spring 31 against the for-

ward follower 16. In buffing the action is reversed, the spring 31 being compressed against the plates 29, 30, and the spring 32 being compressed by the plate 24 against the follower 17. The gear reaches the limit of its compressive movement when the ends of the arms associated with each pair of plates engage the marginal portions of the other pair of plates. The cushioning elements are supported upon the lower longitudinal member of the yoke 15.

The modification of Figs. 4, 5 and 6 comprises the addition of spring seating plates 33, 34, interposed between plates 24 and 30 and their respective springs 31 and 32. The object of these seating plates is to furnish a bearing or seat for the entire end of each spring, instead of only a portion thereof, as in the form shown in Figs. 1, 2 and 3.

The operation of the modification is in all

respects similar to that of the first described form.

I claim as my invention—

In a draft gear for railway cars, a pair of opposed followers, an integral spring enclosure on each follower, each enclosure comprising side plates and cross members, a pair of spaced arms extending forwardly from each side plate of one of said enclosures, reinforcing ribs extending along said plates and the adjacent marginal edges of said arms, a pair of arms having reinforced ribs extending rearwardly from the side plates of the other enclosure between said first named arms and engaging said flanges, a cross member for each pair of arms, seating plates engaging said cross member, and springs in each enclosure between the followers and the seating plates.

HENRY I. WRIGLEY.
